[75] Inventor: R. Marlene Romani, Indiana, Pa.

Primary Examiner—Bernard Ansher

[73] Assignee: M. D. C. Romanic, Inc., Indiana, Pa.

Assistant Examiner—C. Tuttle
Attorney, Agent, or Firm—Michael R. Swartz

[**] Term: 14 Years

[57] CLAIM

[21] Appl. No.: 554,623

The ornamental design for a vacuum attachment for hair grooming clippers, as shown.

[22] Filed: Jul. 18, 1990

DESCRIPTION

[52] U.S. Cl. D28/54

FIG. 1 is a perspective view of a vacuum attachment for hair grooming clippers showing my new design;
FIG. 2 is a right side elevational view thereof, the side opposite being a mirror image of the side shown;
FIG. 3 is a top plan view thereof;
FIG. 4 is a front elevational view thereof;
FIG. 5 is a rear elevational view thereof; and,
FIG. 6 is a bottom plan view thereof.
